UNITED STATES PATENT OFFICE.

EUGENE L. DE VERE, OF CHICAGO, ILLINOIS.

RESILIENT SHOE HEEL.

Application filed March 6, 1920. Serial No. 333,384.

To all whom it may concern:

Be it known that I, EUGENE L. DE VERE, a citizen of the United States, residing at Chicago, in the county of Cook and State 5 of Illinois, have invented certain new and useful Improvements in Resilient Shoe Heels, of which the following is a specification.

The invention relates to improvements in 10 resilient shoe heels.

One of the objects of the invention is to provide a resilient heel for shoes that may be sold at a price in competition with a rubber lift.

15 Another object is to provide an inside core for a rubber heel, made of cheaper, and preferably lighter material, such for example as cork, ground leather, sawdust or other fibrous, comminuted material molded into 20 suitable shape and made homogeneous with a binder which will render the composition substantially water proof, resilient to a degree and tenacious.

Another object is to mold a rubber casing 25 and insert the core therein, or to vulcanize the casing around the core.

Another object is to provide perforations for nail holes thru the core, at spaced-apart intervals, to receive the attaching nails and 30 to provide small nicks in the tread surface of the heel, to indicate the position of the respective holes, as guides for driving the nails, thru the structure.

Another object is to shape the core so that 35 a larger quantity of rubber than elsewhere will be included between the rear end and sides of the core and the tread surface of the heel, to produce greater resilience at this part of the heel, and to provide a larger quantity of rubber where the greatest wear 40 occurs and to cushion the impact produced by the foot of the wearer in walking.

Other, further and specific objects of the 45 invention will become readily apparent from a consideration of the following description when taken in conjunction with the drawings, wherein:

Fig. 1 is an inverted plan view.

Fig. 2 is a section taken on line 2-2 of 50 Fig. 1.

Fig. 3 is a section taken on line 3-3 of Fig. 1.

55 In all the views the same reference characters are employed to indicate similar parts.

5 represents a rubber housing or casing

and 6 is the enclosed core of the heel. 7 is the rear portion of the heel and 8 is the front portion. The rubber casing or housing 5 is provided with an edge 10 formed by 60 the concave surface 9 to fit the rounded sole of a shoe. This surface corresponds to the convex surface of the sole underlying the heel, so that when the heel is nailed on to the sole of the shoe, the salient edges 10 will fit closely to the sole, being pressed into contact therewith by the more or less resilient effect of the rubber of which the housing 5 is composed. The core 6 is turned upwardly at its ends, as at 11, and the housing 70 is provided with a surrounding rim 12 which holds the core in place when the core and the housing are made separately and the core inserted therein. If the housing is vulcanized around the core, which it may be, then 75 the portion between the two lines, as at 13', will cover the core and entirely enclose it, a part of this being the bead shown at 12.

The core may be made of granular, or 80 comminuted fibrous material, such, preferably as cork molded into form by use of a suitable binder which will produce a homogeneous material, and render the material more or less resilient and light and well adapted for the purpose. Ground leather, 85 saw dust, or other light fibrous substances such, for instance as papier mâché, suitably coated, or fibrous asbestos capable of withstanding the temperature of vulcanization, may be employed when the core is to be 90 entirely enclosed within the rubber casing.

The core may have nail holes or perforations 13 at intervals thru which to drive nails to hold the heel in place and the rubber coating on the tread surface of the heel may 95 have nicks or indentations 14 in line with the respective holes to indicate the holes and to enable the nail to be more readily driven thru the structure.

When the heel is in place the core as well 100 as the rubber covering will be securely held on the shoe.

When the nails are driven thru the structure, the heads may be submerged in the rubber below the rubber tread surface with 105 their heads resting on the harder and less resilient core.

In making the heel for an insertable core, the core covering of rubber is chambered out to receive the core. It is well that the chamber should be somewhat smaller than the dimensions of the core so that it becomes 110

necessary to extend or stretch the rubber when inserting the core. This serves to hold the cover more intimately in contact with the core and it slightly flares the vertical edges of the heel to make it conform to the standard type of heel.

Having described my invention, what I claim as new and desire to secure by Letters Patent is:—

- 10 A heel comprising a block of resilient material having its upper face cored out to leave the sides and bottom relatively thin;

a core of relatively rigid, light material having its rear and side edges rounded, tapering and sharply bent upwardly near its immediate edges and leaving its front edge in a horizontal plane and of uniform thickness, said core adapted to fit neatly within the cavity of the block, and a covering of impervious material on top of the core, and sealed to the edges of the block.

In testimony whereof I hereunto subscribe my name.

EUGENE L. DE VERE.
